UNITED STATES PATENT OFFICE.

LEONARD BARTELMEH, OF WILKINSBURG, PENNSYLVANIA.

DESIGN FOR A SERVICE-BUTTON.

53,482.

Specification for Design.

Patented July 8, 1919.

Application filed March 7, 1919. Serial No 281,318. Term of patent $3\frac{1}{2}$ years.

To all whom it may concern:

Be it known that I, LEONARD BARTELMEH, a subject of the King of England, residing at Wilkinsburg, in the county of Allegheny and State of Pennsylvania, have invented a new, original, and ornamental Design for a Service-Button, of which the following is a specification, reference being had to the accompanying drawing, forming part thereof.

The figure is a face view of a service button, showing my new design.

What is claimed is:

The ornamental design for a service button, as shown in the accompanying drawing.

LEONARD BARTELMEH.

Witnesses:

LEWIS H. BAKER,
ASA BENTLEY.
